UNITED STATES PATENT OFFICE.

DANIEL A. BRUBAKER, OF DUNCANSVILLE, PENNSYLVANIA.

TRACK-FASTENING AND TIE.

No. 909,144.

Specification of Letters Patent. Patented Jan. 12, 1902.

Application filed March 9, 1908. Serial No. 419,983.

To all whom it may concern:

Be it known that I, DANIEL A. BRUBAKER, a citizen of the United States, residing at Duncansville, in the county of Blair and State of Pennsylvania, have invented certain new and useful Improvements in Track-Fastenings and Ties, of which the following is a specification.

The present invention relates to railway ties and has specially in view a metallic tie which will possess all the advantages of the ordinary wooden tie in so far as the means for detachably supporting the rails is concerned, and being further provided with improved means for causing the tie to firmly engage with the roadbed so as to avoid all danger of creeping of said tie.

With the above and many other objects in view, the invention contemplates a metallic tie of hollow formation in which improved means are provided for detachably carrying wooden blocks to which the rails are spiked in the usual manner, said blocks being retained in a rigid position relative to the metallic portion of the tie, and being arranged whereby there is no contact between said rails and the said metallic portion of the tie, the metallic portion of the tie being also provided with means which will interlock with the roadbed and serve to retain said tie in a fixed position relative to said roadbed.

In carrying out the objects set forth above various forms of the invention may be employed, a preferred embodiment of which is shown in the accompanying drawings, in which—

Figure 1 is a perspective view of the tie with the rails supported thereon. Fig. 2 is a longitudinal sectional view thereof. Fig. 3 is a bottom plan view of the tie, one end thereof being broken off. Fig. 4 is a perspective view of one of the wooden track supporting blocks.

Like characters of reference designate corresponding parts.

Referring to said drawings, 10 designates a hollow metallic tie, the bottom central portion 11 of which is bulged outwardly to form a slightly depending central bottom surface having central and end ribs 12 and 13, preferably arranged in pairs and adapted to engage with the roadbed, as will be more fully set forth later.

55 The central portion of the tie, between its top and bottom has a centrally located ver-

tical strengthening rib 14, which divides said central portion into two open-ended transverse chambers 15—16, and adjacent to each extreme end of the tie, open-ended chambers 17 and 18 respectively are also formed transversely through the tie, said end and central chambers serving to receive a portion of the roadbed ballast when the tie is in position, as will presently appear.

Between the central transverse chambers and each transverse end chamber, the tie is provided with an open keeper pocket 19 one end wall 20 of which is inclined and presents a smooth surface, the opposite end wall 22 being provided with a horizontal locking rib 23 which has upper and lower inclined sides and projects inwardly toward the center of the recess, the construction of which is shown more clearly in Fig. 2 of the drawings. The said pockets 19 in the tie are designed to form seats or keepers for rail supporting blocks 25. These blocks are of wedge-form to fit and wedge against the inclined ends of the pockets, and one side of each block 25 is provided with a notch 27 with which the rib 23 of the wall 22 interlocks when the block is seated in the pocket. Said blocks are of wood and are arranged in their respective pockets in such a manner that their upper surface will project beyond the upper surface of the tie and thereby prevent any contact of the rails with the metallic portion of the tie, as well as providing an effective surface for the ready attaching of the rails by means of the usual spikes, as is clearly shown in Fig. 1 of the drawings. To assist in retaining said blocks in their pockets, bolts 28 may be passed through the tie and the blocks, openings 29 being formed through the inner ends of the blocks to facilitate the passage of the bolts.

Referring to Figs. 2 and 3 of the drawings, it will be observed that the ribs 13 of the bottom bulging surface of the tie are correspondingly arranged and extend from opposite sides of the tie to the center thereof. The center ribs 12 are oppositely arranged and also extend from opposite sides of the tie, but their arrangement is such that they present to one another, at their meeting centers, a point.

It will be understood that when the tie is placed on a roadbed and the ballast placed around it, the bottom ribs will engage with such ballast, and also the central and end transverse chambers will have the ballast

forced therein, thereby causing what may be termed an interlocking engagement between the tie and the ballast, which, when the ballast has properly set, will firmly retain the 5 said tie in position.

It will be observed that the supporting surface of the rail supporting blocks is of a rectangular shape, which in addition to providing ample space for the spiking of 10 the rails thereto, also affords ample space for the reception of signal supporting mechanism, and as the blocks are of insulating material, they effectually insulate such mechanism from the tie.

15 Claims:—

1. A metallic tie provided with a pocket adjacent to each end, one end wall of each pocket being inclined and the other end wall being provided with a horizontal rib, and

a wooden rail supporting block adapted to 20 be seated in said pocket, said supporting block being provided with an end wall which is inclined and adapted to wedge against the inclined wall of the pocket, the other end of the said supporting block being provided 25 with a notch with which the ribbed wall of the pocket interlocks.

2. A railway tie provided with detachable rail supporting blocks, said tie being also provided with an enlarged central portion 30 forming open-ended chambers the bottom of which has ribs formed thereon.

In testimony whereof I hereunto affix my signature in the presence of two witnesses.

DANIEL A. BRUBAKER.
